UNITED STATES PATENT OFFICE.

ALFRED GLIDEWELL, OF FAYETTEVILLE, TENNESSEE.

DESIGN FOR A PACK OF PLAYING-CARDS.

52,986.

Specification for Design.

Patented Feb. 11, 1919.

Application filed May 18, 1918. Serial No. 235,421. Term of patent 3½ years.

To all whom it may concern:

Be it known that I, ALFRED GLIDEWELL, a citizen of the United States, and a resident of Fayetteville, in the county of Lincoln and State of Tennessee, have invented a new, original, and ornamental Design for Packs of Playing-Cards, of which the following is a specification, reference being had to the accompanying drawing forming part thereof.

The drawings show the various cards, except duplicates, contained in the pack and illustrate my new design.

I claim:—

The ornamental design for a pack of playing cards, as shown.

ALFRED GLIDEWELL.
